[57] CLAIM

The ornamental design for an electric dry shaver, substantially as shown and described.

DESCRIPTION

FIG. 1 is perspective view of the front and right side of an electric dry shaver showing our new design.

FIG. 2 is a top plan view thereof the continuous perforation pattern and toothed pattern being shown partially for ease of illustration.

FIG. 3 is a bottom plan view thereof.

FIG. 4 is a left side elevational view thereof.

FIG. 5 is a front elevational view thereof.

FIG. 6 is a right side elevational view thereof.

FIG. 7 is a rear elevational view thereof the continuous perforation pattern being shown partially for ease of illustration.

FIG. 8 is a front elevational view of the lower half of an electric shaver showing a second embodiment of our new design which corresponds in all respects to the electric shaver shown in FIGS. 1 through 7 except that the sides of the shaver are non-idented towards the bottom of the shaver.

FIG. 9 is an elevational view of the right side of the shaver as seen in FIG. 8, the left side of the shaver being identical with the right side; and

FIG. 10 is a bottom plan view of the shaver shown in FIGS. 8 and 9.
